UNITED STATES PATENT OFFICE

LYMAN C. HUFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PUMP VALVE

Application filed April 21, 1926. Serial No. 103,478.

This invention relates to improvements in pumps, and refers more particularly to a pump provided with a ball valve which is guided in its movement by a novel form of guiding member comprising spaced fingers.

More specifically, the present invention is particularly directed to a novel form of guide for a ball valve in combination with a removable closure cap over the valve port to be used 10 either in surge blocks or directly in the liquid end of an oil pump.

The present invention is particularly adapted for use in pumps handling oil heated to high temperatures.

15 The main advantage of the type of ball valve guide which will be described in the following specification is that it is very simple in design and permits a maximum free opening around the ball through which the liquid can pass. Heretofore, in pumps using ball valves, it has been the practice to seat the ball in a sleeve or cylinder provided with large perforations through which the oil can pass. One of the objections to this sleeve or 20 cylinder is that it obstructs the flow of oil through the valve seat, and, in addition, forms pockets into which carbon and other sediment can accumulate, necessitating frequent removal of the valves for cleaning.

25 The design of the present invention eliminates these objections, and particularly contemplates that there shall be no obstruction to the flow of oil except the narrow guide fingers which project inwardly to guide the movement of the ball.

30 Another desirable feature of the present invention is the closure cap over the valve port and the method of holding it in place. This cap is removably held on a seat by means of a screw plug.

35 Various other advantages and objections will be more apparent from the following description.

In the drawings, Fig. 1 is a side elevational view, with parts in dotted lines, of a surge 45 block equipped with the present invention;

Fig. 2 is a cross-sectional view on line 2—2 of Fig. 1;

50 Fig. 3 is a cross-sectional view on line 3—3 of Fig. 4, and

Fig. 4 is a side elevational view, with parts in dotted lines, of a duplex reciprocating pump.

In the drawings, and referring more particularly to Figs. 1 and 2, 1 designates a surge 55 block or casting which may be of forged steel or other metal. This block is provided with the suction inlet 2 and discharge 3. As shown in dotted lines, the suction pipe 2 extends for a considerable distance into the 60 casting 1. Adjacent the opposite end from the discharge 3 is a plurality of valve ports designated diagrammatically at 4, controlled by ball valves 5 mounted on the seats 6. These ball valves 5 are more particularly 65 shown in Fig. 2. The seats 6 may, if desired, have screw threaded engagement with the casting surrounding the valve ports 4.

Describing now as a feature of the present invention the guide and closure cap, the guide 70 may take the form of a projection 7 terminating in the outwardly flaring, separated, curved fingers 8. The area of curvature of the curved fingers 8 is slightly greater than the circumferential area of the ball 5 to permit ready movement of the ball in the guide 75 but preventing excess play. The projection 7 is preferably made as an integral part of the closure cap 9, although it is understood, of course, that they may be made in any number 80 of parts and connected together. The closure cap 9 is provided with an outwardly flaring offset portion 10 on its outer side, which is adapted to form a shoulder seating 85 on the shoulder or seat 11 formed in the opening above the valve port.

The arrangement is such that in assembling, the ball 5 is first placed on the seat 6 to close the valve port 4. The cap 9 carrying the fingers 8 is then dropped into place, 90 the offset shoulder 10 making contact with the seat 11. In order to hold the cap 10 firmly in position on the seat to prevent chattering and wear, a screw plug 13 is screwed 95 into the opening above the valve port until its inner surface contacts with the surface of the cap 9.

As another advantageous feature of the present invention, the inner surface of the screw cap 13 is curved, as shown at 14, being 100

adapted to contact a similar curved surface 15 on the closure cap 9, thus permitting contact between the two caps at substantially a center point so as to permit the closure cap 9 to adjust itself to any irregularities in the seat. A surge connection 16 communicates with the valve ports 4 on both the suction inlet and discharge. The line 17 serves as a connection to a pump.

10 I have referred particularly to and have described the valve ports and valves shown in the end of the surge block remote from the point of discharge, but it is obvious that the same type of valve is used immediately adjacent to the point of discharge. Therefore, I have used the same reference characters.

15 The course of the oil is best illustrated by the arrows in Fig. 1. The disc forming the closure cap 9 is preferably of aluminum bronze, as is also the screw plug 13, although any other metal may be used which is found suitable.

20 The illustrations in Figs. 3 and 4 are not modifications of the ball valve guide and closure cap, but are merely illustrative of the use of the ball valve guide and closure cap of the present invention in a duplex reciprocating pump, as distinguished from a surge block.

25 30 Briefly describing Figs. 3 and 4, 1' designates the pump casting provided with suction inlet 2' and discharge 3'. As shown more particularly in Fig. 3, in a duplex pump there are two suction inlets. The suction inlets discharge the liquid through the valve ports 4', normally closed by means of the ball valve 5' held on seat 6'. A projection 7' provided with curved fingers 8' is connected to a closure cap 9'. This closure cap 9' has an offset shoulder portion adapted to contact with a seat in the same manner as was described in Figs. 1 and 2. A screw plug 13' is adapted to hold the closure cap 9' in place. The oil passing through the valve ports 4' will raise the ball valve 5' from its seat and will flow through the ducts 18, being forced by the pistons 19 through the upper valve ports 4', and eventually through the discharge 3'. The piston 19 is carried on the usual shaft 20 reciprocating in the casting 1. Cooling water may be introduced through the inlet 21, controlled by valve 22, to the jacket 23, being discharged through the line 24, controlled by valve 25. The usual 35 flexible packing 26 and inlet 27 for cooling liquid, controlled by valve 28, is provided. It will be instantly apparent to those skilled in this art that the ball valve guide of the present invention permits a maximum free 40 opening around the ball through which the liquid can pass.

45 In assembling, the closure cap 9 carrying the fingers 8 can be dropped into place, and the joint between it and the pump casing 50 ground in with any tool suitable for this

purpose. After having been ground in, the faces are cleaned and the cap again inserted. The screw plug 13 is then screwed into place and caused to bear down on the closure cap 9, holding it in contact with the ground seat 70 11.

75 This arrangement for holding the cap 9 in place is simple and unique. It requires a minimum amount of space as compared with any method of holding the cap in place by means of a yolk bolted to the pump casing.

80 I have found that preferably the closure cap 9 and holding screw plug 13 should be two separate pieces so that the closure cap 9 can be ground in separately. The point of contact between the two caps is preferably at the center, as heretofore described.

85 The projection 7 may be provided with any number of fingers, say from 4 to 8 more or less, serving to guide the ball and keep it at all times directly over the seat.

90 I claim as my invention:

95 1. The combination with a casing, of a valve seat member having a port therein, a ball valve normally closing said port, a closure cap adapted to be inserted over said port and ball, said closure cap being provided with a projection terminating in spaced guide fingers adapted to surround the ball out of contact with said seat member, said cap having removable engagement with a seat in the casing, and an auxiliary screw plug adapted to have screw-threaded engagement with the casing in substantial alignment with said closure cap. 100

105 2. The combination with a casing, of a valve port therein, a ball valve normally closing said port, a closure cap adapted to be inserted over said port and ball, said closure cap being provided with a projection terminating in spaced guide fingers adapted to surround the ball, said cap having removable engagement with a seat in the casing, and an auxiliary screw plug adapted to have screw threaded engagement with the casing, the inner surface of said screw plug being adapted to bear against the surface of the first mentioned closure cap to hold the latter on its seat. 110

115 3. The combination with a casing, of a valve port therein, a ball valve normally closing said port, a closure cap adapted to be inserted over said port and ball, said closure cap being provided with a projection terminating in spaced guide fingers adapted to surround the ball, said cap having removable engagement with a seat in the casing, and an auxiliary screw plug adapted to have screw threaded engagement with the casing, the inner surface of said screw plug being adapted to bear against the surface of the first mentioned closure cap to hold the latter on its seat, contacting surfaces of said screw plug and closure cap being curved so that contact is made at substantially a center 120 125 130

point, permitting the closure cap to adjust itself to irregularities in the seat.

4. The combination with a casing, a valve port therein, a ball valve normally closing said port, a closure cap adapted to be inserted over said port and ball, said closure cap being provided with a projection terminating short of said port in spaced guide fingers adapted to surround said ball, said cap having removable engagement with a seat in said casing, and a screw plug within said casing for holding said cap in engagement with its seat.

5. The combination with a casing, a plurality of valve ports in said casing, an individual opening in said casing for each valve port, an individual closure cap insertable through each of said openings, each closure cap having a rigid projection terminating in spaced fingers, a ball valve normally closing each valve port and surrounded by said spaced fingers, and individual means co-operating with each of said individual openings in said casing for holding said closure caps in closed position.

6. The combination with a casing, a plurality of valve ports in said casing, an individual opening in said casing for each valve port, an individual closure cap insertable through each of said openings, each of said closure caps carrying a seat, corresponding seats carried by the casing interiorally thereof, and each closure cap having a rigid projection terminating in spaced fingers, a ball valve normally closing each valve port and surrounded by said spaced fingers, and individual means co-operating with each of said individual openings in said casing for holding said closure caps in closed position.

7. The combination with a casing, a valve port therein, a ball valve normally closing said port, an opening in said casing individual to said valve port, an individual closure cap adapted to be inserted over said port and ball, said closure cap being provided with a rigid projection terminating in spaced guide fingers adapted to surround said ball, said individual cap having removable engagement with an individual seat positioned interiorally of said casing, and means threadedly engaging said opening and arranged to contact said cap centrally thereof and hold the same in engagement with its seat.

LYMAN C. HUFF.
